ATTORNEY

UNITED STATES PATENT OFFICE

ELLA M. ADAMS, OF NEW YORK, N. Y.

HAIR WAVER

Application filed April 5, 1929. Serial No. 352,727.

This invention relates to a permanent Marcel waving member and particularly to a member adapted to have strands or locks of hair laced or intertwined back and forth upon one side and engaged within indentations formed along opposite side edges.

The general object of my invention is to provide a simple and practical form of permanent marcel waving member which will hold the strand of hair which is looped thereon while being baked without unduly stretching the same.

With the above and other objects in view, my invention includes the features of construction set forth in the following specification and illustrated in the accompanying drawing.

In the accompanying drawing annexed hereto and forming a part of this specification I have shown my invention embodied in a simple form of hair marcelling or looping member, but it will be understood that the invention can be otherwise embodied and that the drawing is not to be construed as defining or limiting the scope of the invention, the claims appended to this specification being relied upon for that purpose.

The figure of the drawing shows a perspective view of a Marcel waving member in accordance with the present invention and having hair positioned thereon preparatory to being inserted in the heating tube.

In the above mentioned drawing I have shown but one embodiment of the invention which is now deemed preferable, but it is to be understood that changes and modifications may be made within the scope of the appended claims without departing from the spirit of the invention.

Referring more in detail to the figure of the drawing I provide a thin plate 10 made of sheet metal or other material that may be readily shaped and maintained permanent in its predetermined shape. This plate 10 may conveniently be made by stamping or cutting it from sheet metal, but other materials, preferably non-inflammable, may also be employed. The plate or sheet 10 may be laterally curved slightly and uniformly throughout its length. Extending from the

opposite sides of the plate 10 are a plurality of wedge shaped projections 13-14 which form a series of V-shaped notches 11 between adjacent projections. The projections 13, which I shall call the hair loop compressing projections, are preferably wider than the projections 14 which I shall call the hair loop supporting projections. The projections 13 alternate with the projections 14 on each side of the plate 10. The projections on opposite sides of the plate are preferably approximately opposite each other. A strand of hair 12 is looped around the projections 14. The function of the projections 13 is to cooperate with the projections 14 so as to grip and compress the strand of hair between the projections 13-14. The use of the extra projections 13 makes it possible to retain the hair on the plate without stretching the hair or destroying the fluffiness of the parts of the strand that lie on the face of the plate.

Between the indentations on opposite sides a relatively wide, smooth, and if desired a slightly curved surface is presented over which portions of the strand or lock of hair 12 extends. The strands of hair 12 being waved or marcelled, except when passing around the projections 14 between the indentations 11, remain upon one side only of the plate 10. The lock of hair 12 when removed from the plate 10 will therefore be substantially flat and have a number of undulations simulating "Marcel" waves.

In operation the hair 12 being curled or marcelled is combed or brushed out and a small amount or lock 12 is wrapped back and forth between opposite sides as indicated in the figure and intertwined about the projections 14 on the side edges of the plate 10. A large number of these plates 10 are employed in waving the hair and the strands of hair 12 are positioned thereon while the hair is suitably moistened with any usual preparation used with the waving operation. When the hair in individual locks 12 has been suitably wrapped upon a plurality of these plates 10 the individual plates 10 are inserted within electric heating cups or tubes which may preferably have elongated narrow openings with in which these plates are inserted. When

the hair has been suitably heated the cups or tubes are removed and the hair taken from the plates 10 after which the undulations are slightly brushed out to give the hair a uniform Marcel effect.

- 6 In positioning the hair 12 upon the plate 10 it is maintained upon one side of the plate 10, being looped around projections 14 on opposite sides of the plate and being engaged and held between the projections 13 and 14. 10 This gives the hair 12, when removed from the plate 10, a flat Marcel wave effect with small and closely adjacent undulations which are adapted to lie closely against the scalp. The 15 plate 10 over which the hair 12 is positioned is entirely sanitary and may be easily sterilized by boiling or washing in the usual manner.

I claim:

- 20 1. In a hair waving device, a plate having a plurality of hair loop supporting and hair loop compressing projections defining a plurality of V-notches extending inwardly from the opposite sides thereof, said notches being adapted to receive a strand of hair looped over every second projection between said notches the alternate projections being adapted to compress and hold the curved portions 25 of the strand without subjecting the intermediate portions thereof to substantial tension or destroying the fluffiness of such intermediate portions.
2. In a hair waving device, a plate having a plurality of wedge shaped projections extending from the opposite sides thereof and forming V-shaped notches between adjacent projections, said projections forming alternating hair loop supporting and hair loop compressing projections.
- 30 3. In a hair waving device, a plate having a plurality of wedge shaped projections extending from the opposite sides thereof, said projections defining a plurality of V-shaped notches between adjacent projections, the projections on the opposite sides of said plate being approximately opposite each other, said projections being adapted to frictionally grip and compress a strand of hair when said strand is looped from side to side of said plate around alternate projections.
- 35 4. In a hair waving device, a plate having a plurality of wedge shaped projections extending from the opposite sides thereof and forming V-shaped notches between adjacent projections, the projections on each side of said plate being alternately broad and narrow.

ELLA M. ADAMS.
